RAILWAY DRAFT APPLIANCE

William J. Regan, Pittsburgh, Pa., assignor to
The McConway & Torley Company, Pittsburgh,
Pa., a corporation of Pennsylvania

Application July 10, 1928. Serial No. 291,655

9 Claims. (Cl. 213—12)

My invention relates to railway draft appliances and is particularly concerned with the production of a lightweight coupler of the radial type associated with a draft and buffing gear to 5 which buffing and pulling forces are always communicated in the direction of the axis of the gear.

The principal feature of the invention consists in mounting the draft gear upon the shank of the car coupler in advance of the tail pin or axis 10 about which the coupler swings, the coupler being slotted at its rear end to receive the tail pin and being thereby slidably as well as rotatably mounted upon the car.

Other features of the invention relating to advantageous combinations of parts and details of construction will hereinafter appear and be particularly pointed out in the claims.

In the drawings illustrating preferred embodiments of the invention:

20 Figure 1 is a plan view of a draft appliance constructed in accordance with the invention.

Figure 2 is a detail sectional view on the line 2—2, Figure 1.

Figure 3 is a detail central sectional view, the 25 draft bolt being in plan.

Figure 4 is a detail vertical sectional view, the tail pin and a portion of the draft bolt being in elevation.

Figure 5 is a rear end elevation of the construction shown in Figures 1 to 4 inclusive.

Figure 6 is a detail view, partly in plan and partly in horizontal section illustrating a modified form of the invention.

Figure 7 is a detail vertical sectional view of 35 the construction shown in Figure 6, the followers and tail pin being in elevation.

Figure 8 is a rear end elevation of the modified form of the invention.

In the drawings, 1 indicates a car coupler of 40 the laterally swinging or radial type pivotally connected to the car upon which it is mounted through the intermediacy of a tail pin 2 and a pivot casting or anchor member 3. While a particular form of coupler head 4, knuckle 5 and locking mechanism 6 have been illustrated in the drawings it is to be understood that they are not material to the invention.

The shank 7 of the coupler has vertically spaced 50 rearwardly extending arms or straps 8 cast integrally with the coupler head. They may be made of light section as they are subject to pulling or tension strains only, buffing forces being transmitted from the coupler head independently of said arms. Upon their opposed inner faces the 55 top and bottom members 8 of the coupler shank

are formed with pulling shoulders 9 adapted to cooperate with a rear follower 10 mounted between the shank members 8 so as to be relatively slidably with respect thereto. During a buffing operation the follower 10 transmits the buffing 60 shock to the anchor casting 3. To permit the follower thus to transmit buffing forces to the anchor casting in all laterally displaced positions the coupler may occupy the follower is curved upon its rear side and the anchor casting 65 3 is correspondingly curved, the latter preferably being formed for this purpose with vertically spaced horizontal members 11 having forward faces 12 curved concentric with the axis of the tail pin 2, and the follower 10 being provided 70 with correspondingly curved rearwardly facing surfaces 13 for cooperating therewith. To the rear of the pulling shoulders 9 the arms 8 of the coupler shank are provided with vertically aligned longitudinally extending slots 8a for receiving 75 the pivot pin 2, the slots being of such length and so positioned with respect to the pulling shoulders 9 that the portion of each slot which is in advance of the pivot pin when the coupler is in normal position is slightly longer than the movement or travel of the draft and buffing spring 14 forming a part of the construction, while the clearance in the slots to the rear of the pivot pin 2 is slightly less than the spring movement.

The spring 14 which is mounted between the 80 arms of the coupler shank bears at its rear end against the follower 10 and at its forward end against the follower 15 secured to a draft bolt 16 passing through the spring. As a means for connecting the front follower 15 to the draft bolt 90 90 these members are preferably provided with cooperating screw threads, as shown in Figures 3 and 4. To guide the forward follower and preserve the alinement of the draft bolt 16 with respect to the shank of the coupler when the latter 95 swings in either direction from its normal or central position, the coupler shank is provided adjacent the forward ends of its arms 8 with laterally disposed walls 17 which extend rearwardly sufficiently far to overlap the forward follower 100 15 when the spring 16 is fully compressed in pulling.

The draft bolt 16 which extends through the follower 10 is fashioned to the rear of that follower with an enlargement 16a provided with a 105 slot 18 for receiving the tail or pivot pin 2. As shown in Figures 3 and 4 the pin 2 is normally positioned at the rear end of the slot in the draft bolt and the portion of said slot 18 in advance of said bolt is as long as the portions of the slots 8a 110

of the coupler shank which extend forwardly of the bolt, thus providing the necessary clearance to relieve the draft bolt 16 from strain when the spring 14 is compressed by a buffing or pushing 5 load.

The pivot pin 2 by which the coupler and draft gear are connected to the anchor casting 3 extends through corresponding vertically aligned openings 19 in the horizontal members 11 of the 10 pivot casting, the said bolt preferably being inserted from below and having at its upper end a nut 20 which bridges the slot 8a in the upper arm 8 of the coupler shank.

The device for anchoring the coupler and draft gear to the car body is preferably formed as an integral casting having an upper plate-like portion 21 suitably perforated to receive securing bolts or rivets and having laterally spaced downwardly extending webs 22 which diverge forwardly from the pivot pin 2 so as to afford clearance for the swinging movements of the coupler. The horizontal bars 11 against which the rear follower 10 of the draft gear is seated in buffing are integrally united at their ends to the depending 25 webs or flanges 22.

By extending the top and bottom slotted members 8 of the coupler shank rearwardly of the pulling shoulders 9 and the tail pin 2 means are provided for maintaining the rear of the coupler 30 in proper relation to the draft bolt 16 while allowing the coupler to have both sliding and pivotal movements with respect to the pivot casting 3. By this means also when the pulling load is nearly equal to the capacity of the spring 14 the pivot pin 2 is placed in quadruple shear and the 35 load is then divided between the coupler shank straps 8 and the draft bolt 16 due to the pivot pin coming in contact with the top and bottom shank straps at the rear ends of the slots 8a therein.

In assembling the coupler and draft gear shown 40 in Figures 1 to 5 inclusive the front follower 15 is inserted in the shank of the coupler and seated upon the follower abutment wall 23 at the forward ends of the top and bottom straps 8 of the coupler shank. The spring 14 is then placed in 45 position and the rear follower 10 is inserted from the side between the shank arms so as to bear against the corresponding stops or pulling shoulders 9. By means of a headed bolt inserted 50 through the rear follower 10 and threaded into the forward follower 15, the spring is then compressed by pulling the forward follower rearwardly about an inch, after which a key, wedge or the like is temporarily inserted through an opening 55 24 provided for that purpose at the guard arm side in the shank of the coupler opposite the front follower. The bolt that has been employed to compress the spring 14 is then removed and the draft bolt 16 is inserted through the rear follower and screwed into the forward follower 15. The key or wedge that has been inserted in the 60 opening 24 of the coupler shank to hold the spring temporarily compressed is then removed, leaving the coupler and draft gear ready for application to the pivot or anchor casting 3. As the tail pin 2 prevents the draft bolt 16 from unscrewing and as the forward follower cannot turn because of its engagement with the coupler shank, it is impossible for the coupler and draft gear to become 65 accidentally disassembled.

When subjected to draft the shank arms 8 of the coupler acting through the rear follower stops or pulling shoulders 9 cause the spring 14 to be compressed against the front follower 15, which latter is held against the forward movement by 70

the draft bolt 16. Pulling stresses are thus communicated to the tail pin 2 and thence to the pivot casting 3. When a buffing force is applied to the coupler the wall 23 thereof which engages the forward follower 15 causes the latter to press rearwardly against the spring 14 and the latter is compressed against the rear follower 10 which is then seated against the cross bars 11 of the anchor casting. 80

In the form of the invention illustrated in Figures 6, 7 and 8 pulling forces applied to the coupler are communicated to the anchor casting through a draft yoke instead of through a draft bolt. In this construction the shank of the coupler 25 is formed with upper and lower rearwardly extending arms or straps 26 provided at their rear ends with elongated slots 27 for receiving a pivot or tail pin 28 extending through corresponding vertically aligned pivot openings 29 in the horizontal bars 30 of an anchor casting 31 adapted to be secured to the car body, the slots 27 preferably having the same length and relation to the tail pin as heretofore described in respect to the slots 8a and tail pin 2. Integrally connecting the shank arms 26 are a web or wall 32 100 forming a front follower stop and a web or wall 33 constituting a rear follower stop, each of these stops being centrally apertured as at 34 and 35 respectively to receive the corresponding stud or post of the adjacent follower. 105

The yoke 36 by which draft forces are transmitted from the coupler to the pivot casting 31 is preferably in the form of a strap having horizontally spaced arms 37 which are received between the top and bottom arms 26 of the coupler shank, 110 its rear end 38 being circularly curved to conform to the correspondingly curved forward surface 39 of the cross wall 40 of the anchor casting. This cross wall against which the rear end of the yoke bears in buffing is preferably reinforced by rearwardly extending marginal ribs or flanges 41 and it is curved concentric with the pivot pin. 115

Disposed between the arms 37 of the yoke are the draft and buffing spring 42, the rear follower 43 and the front follower 44, the spring being interposed between the followers in the usual manner. The follower 43 is provided with a centrally disposed rearwardly extending stud or post 45 which projects through the corresponding opening 35 in the follower stop wall 33 of the coupler shank and bears at its inner end against the forward face 46 of a filler member 47 rigidly secured between the yoke arms 37 by means of rivets 48. This filler 47 has a pivot opening 49 120 for receiving the tail pin 28, the opening being slightly larger than the diameter of the pivot pin so as to permit buffing strains to be delivered directly from the yoke to the cross wall 40 of the pivot casting, thereby relieving the tail pin 28 125 from shearing strains during a buffing operation. 130

The forward ends of the yoke arms 37 are bent inwardly or shouldered to overlap a block 50 which serves to maintain the forward ends of said arms in proper spaced relation, the spacer 50 being rigidly secured to the arms of the yoke by horizontally extending rivets 51. The front follower 44 normally engages the rear face of the spacer 50 and the post 52 with which this follower 135 is provided extends through a corresponding opening 53 in the spacer as well as through the opening 34 in the front follower stop of the coupler shank, the post being of sufficient length to engage the transversely extending wall 54 or 140

abutment connecting the forward ends of the arms 26 to the coupler shank.

The coupler shank straps 26 and the yoke 36, being subject to tension stress only, may be of comparatively light sections, the yoke preferably being made of wrought iron or rolled steel.

To assemble this form of coupler and draft gear the rear follower 43, spring 42, front follower 44, spacer block 50 and the filler member 47 are positioned between the top and bottom straps 26 of the coupler shank. The forward ends of the yoke arms 37 are then sprung apart sufficiently to allow the yoke to pass over the parts placed between the arms 26 of the shank, after which the front end of the yoke is closed against the sides of the forward filler block or spacer 50 and the latter as well as the rear filler member 47 is riveted to the yoke. The coupler and draft gear as thus assembled may then be slidably and pivotally attached to the anchor casting 31 by means of the tail pin 28, which may be of the headless type and be retained in assembled position by means of a cotter 55 passing therethrough and through the lower pivot boss of the anchor casting.

In this form of construction pulling stress is transmitted to the rear follower 43 through the straps 26 of the coupler shank and the rear follower stop integral therewith. The forward movement of this follower thus induced causes the spring 42 to be compressed against the forward follower 44 which bears against the spacer 50 secured to the forward end of the yoke 36. The pulling stress thus communicated to the forward end of the yoke is transmitted rearwardly through the yoke arms 37 to the rear filler block 47 and thence to the tail pin 28 carried by the anchor casting. When the coupler 25 is subjected to buffering the force is transmitted directly from the coupler head to the front follower 44, and thence through the spring 42 and rear follower 43 to the filler member 47 and the rear end of the yoke and from the latter finally to the cross wall or abutment 40 of the pivot casting 31. The invention provides a construction consisting of few and comparatively light parts in which the draft and buffering gear is located in the shank of the coupler and forms an assemblage which may be fitted up complete and shipped or carried in stock for repairs as a unit. It will also be perceived that the invention provides simple and effective means for maintaining the draft gear in direct alignment with the draft and buffering shocks to which the coupler is subjected in any position it may occupy.

I claim:

1. A railway draft appliance comprising a car coupler having a shank provided with oppositely disposed slotted arms and having spaced shoulders forming follower stops, followers disposed between said arms, said followers being respectively adapted to cooperate with said shoulders, a spring interposed between the followers, and a draft bolt connected to one of said followers and extending through and slidably with respect to the other follower, said draft bolt being provided with a slot, a tail pin extending through the slots of said shank arms and through the slot of the draft bolt and means for maintaining said tail pin in assembled relation to the car.

2. A railway draft appliance comprising a car coupler having a head and a shank rigidly connected to said head, said shank being formed with upper and lower arms provided at their rear ends with elongated slots, a pivot casting having ver-

tically spaced transversely extending members interposed between said shank arms, a tail pin extending through said transverse members and said slots, a draft bolt extending between said transverse members and having an enlarged head formed with a slot for receiving the tail pin, the coupler being provided with a plurality of follower stops, followers spaced longitudinally of the coupler for respectively cooperating with said stops, and a spring interposed between said followers, said draft bolt being connected to the forward follower and being slidable with respect to the rear follower, and the latter being curved on its rear side to cooperate with correspondingly curved forward faces of the transverse members of said pivot casting, said coupler shank being provided adjacent the forward ends of said arms with laterally spaced walls for guiding said forward follower, said walls extending rearwardly so as to overlap said forward follower when said spring is fully compressed in draft.

3. A railway draft appliance comprising a coupler having a head and a shank integrally connected thereto, said shank being provided at its rear end with slotted portions adapted to receive a pivot pin and to transmit draft strains directly to the latter, said slotted portions and said pin constituting means whereby said coupler may be slidably and pivotally connected to a railway car, and draft and buffering means mounted upon said shank.

4. A railway draft appliance comprising a car coupler having a head and shank, said shank being provided with elongated slots for receiving a tail pin and being formed upon its interior with follower engaging shoulders, means including a tail pin for connecting the coupler to a railway car, said coupler being slidably and pivotally movable with respect to the tail pin, and draft and buffering means mounted on said coupler in advance of said tail pin, said last named means including a plurality of followers for respectively cooperating with said shoulders and including a draft bolt which is movable rearwardly with the coupler in buffering, said draft bolt and one of said followers being connected to prevent relative longitudinal movement thereof.

5. A railway draft appliance comprising a coupler having a head and slotted shank, a tail pin extending through the slot of said shank and with respect to which said shank is slidably and pivotally movable, a mounting for said tail pin adapted to be secured to a railway car, and draft and buffering means mounted on the coupler shank, said means including a draft bolt and a plurality of followers, one of which is movable with said bolt and one of which is secured to said bolt so as to be fixed against longitudinal movement with respect thereto, and said means being adapted to communicate draft strains to said mounting through the tail pin and being adapted to communicate buffering strains to said mounting independently of said tail pin, and said draft bolt being movable rearwardly with said coupler in buffering.

6. A railway draft appliance comprising a coupler having a head and shank which are integrally united, means for pivotally connecting said shank to a railway car, and draft and buffering gear carried by said coupler, said gear including spaced followers, a draft bolt limiting the separation of said followers and movable rearwardly with the coupler in buffering, and a spring interposed between said followers, said coupler being provided with shoulders respectively adapted to

communicate movements of the coupler to said said last named means including a draft bolt which is movable rearwardly with the coupler in buffering.

7. A railway draft appliance comprising a coupler having a head and a shank provided at its rear end with elongated slots closed at their rear ends, a tail pin, means for communicating stress from said tail pin to the car body, said tail pin extending through said slots in the coupler shank, and draft and buffering gear carried by the coupler, said gear being adapted to communicate draft strains to said pin and to communicate buffering stress to said means, and said slotted shank being adapted to engage the tail pin to communicate stress directly thereto at the end 15 of the draft movement of said coupler.

8. A railway draft appliance comprising a car coupler having a head and shank which are rigidly connected, means rigidly connected to the car body for engaging and supporting the rear end 20 of said shank, means for slidably and pivotally connecting the coupler to said supporting means, and means supported by said shank for resisting draft and buffering forces applied to the coupler,
